OSCILLOSCOPE PANEL

William B. Wilkens, Gilman, N. H., assignor to Laboratory for Electronics, Inc., Boston, Mass., a corporation of Delaware

Application December 24, 1952, Serial No. 22,874

Term of patent 14 years

(Cl. D26—1)

FIG. I

FIG. 2

To all whom it may concern:

Be it known that I, William B. Wilkens, a citizen of the United States, residing in Gilmanton, in the county of Belknap, in the State of New Hampshire, have invented a new, original, and ornamental Design for Oscilloscope Panel, of which the following is a specification, reference being made to the accompanying drawing, forming a part thereof, wherein:

Fig. 1 is a front view of the oscilloscope panel, showing the novel design; and

Fig. 2 is a top view of the oscilloscope panel shown in Fig. 1.

A characteristic feature of the design shown is the

placement of like colored knobs in distinctive groups on the face of the panel. Color contrasts of individual groups have been indicated on the drawing by appropriately shading those areas of the knobs to which colors are applied.

What is claimed is:

The ornamental design for an oscilloscope panel, substantially as shown and described.
